Application March 1, 1929, Serial No. 343,726,
and in Germany March 1, 1928

14 Claims. (Cl. 23—199)

My invention refers to means for carrying out chemical reactions in the gas or vapour phase. It has particular reference to the synthetical production of ammonia from its elements and 5 more especially to means whereby a gas which shall take part in the reaction, can be heated up to a temperature at which it will be prepared to react with another gas under the influence of suitable catalysts.

10 As is well known to those skilled in the art, gases containing hydrogen, when placed under high pressure and heated to temperatures near and above 400° C. are liable to act on iron and iron alloys, so that those parts of the reaction 15 apparatus which consist of iron and iron alloys, will be gradually destroyed or at least their mechanical resistivity and strength will be impaired so that the life of such apparatus is shortened. Means have already been devised for overcom- 20 ing these difficulties as far as those parts of the apparatus are concerned, such as the autoclaves or converters, in which the gases react with each other. However, hitherto those parts of the apparatus, in which the gases are heated up before 25 reaction, have remained unprotected, which is the more disadvantageous as these pre-heating devices must be made of comparatively large size in order to offer to the gases to be heated up a large surface.

30 Owing to the large surface of these pre-heating devices the transmission of heat could not be rendered sufficiently uniform to prevent local over-heating to temperatures at which a speedy de- 35 struction of the apparatus takes place. If it was desired to obtain a certain average temperature, some parts of the apparatus had to be heated to a higher temperature.

According to the present invention I obviate 40 these drawbacks by heating the gases up to the required temperature, which as a rule is below 500° C. by causing them to flow in countercurrent and in heat exchanging relation to a foreign hot inert gas, for instance nitrogen, which is preferably placed under pressure. By the term "foreign" I wish to distinguish the hot inert gas, such 45 as nitrogen, from the gases about to take part or having taken part in the reaction. I heat the nitrogen or other foreign gas to a temperature which, in order to provide for losses of heat by 50 radiation, is a few degrees higher than the pre-heating temperature, by means of suitable heating devices and in doing so there is no need for carefully avoiding the critical temperature of 500° C., at which hydrogen would exert a detri- 55 mental action on iron or iron alloys, because inert

gases, such as nitrogen, do not exert such influence on iron. I prefer heating the inert gas, such as nitrogen, in a gas furnace either directly or by causing it to pass through a molten metal such as lead, the nitrogen or the like flowing 60 through a heating coil immersed in a bath of molten lead which is maintained in molten condition and at the temperature required by means of some suitable furnace.

Preferably the heating-up of the reaction gases 65 by means of hot nitrogen or the like is utilized only for bringing these gases, which have already acquired a temperature approaching reaction temperature, to this reaction temperature so that the hot nitrogen is required to provide only for 70 the heating-up of the gases within a small range of temperature. To this end the fresh gases designed to react are preferably brought in heat 75 exchanging relation, preferably in counter-current, with the hot gases escaping from the reaction chamber. In this manner the fresh gases are already heated up to a certain temperature approaching reaction temperature, but, in the case of gases containing hydrogen, remaining be- 80 low 400° C., at which temperature hydrogen does not exert any detrimental action on iron. The gases which have thus been preheated to a tem- 85 perature below 400° C., are then brought in heat exchanging relation in countercurrent to the hot nitrogen and are thus heated up to the tempera- 90 ture which is required for the carrying through of the reaction.

If this invention is applied to the synthetic 95 production of ammonia, the new mode of heat- 100 ing gases up, apart from being applied to the fresh gases entering the converters, may also be applied with particular advantage to the purify- 105 ing step preceding reaction. As is well known to those skilled in the art, the hydrogen and other gases used in this reaction contain impuri- 110 ties which, when in contact with the catalysts promoting reaction, are known to exert a detri- mental action on these catalysts, whereby the catalysts are frequently deprived altogether of their catalytic activity. Therefore the gases be- 115 fore being heated up for reaction are as a rule subjected to a purifying process in order to remove all obnoxious impurities. This purifying action is obtained if the gases are passed at an elevated temperature over special purification catalysts and as the reaction which takes place in contact with these catalysts, is only slightly exothermic, more especially if the percentage of impurities is not very great, the losses of heat by 120 radiation must be supplied by heating the gases

up again. This heating-up is preferably carried out also by means of hot nitrogen or some other inert gas.

I prefer placing the hot nitrogen or other inert gas under high pressure.

The reaction between ammonia and hydrogen, if high concentrations by volume are used, is connected with a great development of heat so that the gases leaving the converter have a far

10 higher temperature than the gases entering same, and therefore in such cases the gases entering the converter can be heated up sufficiently by heat exchange with the gases leaving the converter. Therefore the heating-up by means of
 15 hot nitrogen or some other inert gas is particularly useful, as far as the reaction between hydrogen and nitrogen is concerned, mainly in those cases, where the gases are brought to reaction at low concentrations, where the heat developed in
 20 the reaction does not suffice for the heating-up of the entering gases. Similar conditions prevail, when the converters are being heated up before starting the synthetic process or when the contact mass in the converters is partly spent or
 25 less efficient.

In the drawing affixed to this specification and forming part thereof an apparatus embodying my invention is illustrated diagrammatically by way of example.

30 Referring to the drawing, 1 is an oven heated with a mixture of gas and air, the heating gas entering through the burner 2, while air enters through a port 3. In the furnace is mounted a container 4 filled with lead and surrounded by
 35 a casing 5. The gases of combustion from this furnace pass through between the walls of the container 4 and the casing 5 and escape through an exhaust conduit 6. In the molten lead in the container 4 is immersed a heating coil 7 into
 40 which nitrogen under high pressures substantially above atmospheric, for instance 100 atms. is introduced through a pipe 8 leading to a compressor 9. From the bottom end of the heating coil 7 a pipe 10 which is branched at 11, leads
 45 to the inlet pipes 12 of two heat exchangers 13, the exhaust pipes 14 of which are connected by means of a pipe 15 with a heat exchanging device 16 from which a pipe 17, on which a cooler 18 is mounted, leads to the suction side of the compressor 9. 19, 19 are pipes extending through the
 50 heat exchanging devices 13, 13. 20, 20 are reducing valves inserted in the pipes.

In the operation of this device nitrogen under pressure is forced by the compressor 9 through
 55 pipe 8 into the heating coil 7, where it is heated up to the temperature of the molten lead in the container 4. The hot nitrogen under pressure now passes through pipes 10 and 12 into the heat
 60 exchanging devices 13, heating up therein the hydrogen or other gas, which flows through the pipes 19 in countercurrent with the nitrogen. The hot nitrogen under pressure after having transmitted part of its heat to the hydrogen, escapes from the heat exchanging device through
 65 pipes 14 and pipe 15 into the heat exchanging device 16, to transmit the greater part of the heat still stored in it to the fresh nitrogen forced by the compressor 9 through pipe 8 into the heating coil, this fresh nitrogen flowing in countercurrent to the spent nitrogen, which in returning to the compressor through pipe 17, is cooled down
 70 in the cooler 18.

In the lead bath the nitrogen is for instance heated up to 320° C. and its temperature in the
 75 heat exchangers 13 is about 300° C. while on

leaving these heat exchangers the temperature will have dropped to about 230° C. so that the fresh nitrogen forced through pipe 8 will be heated to about 225° C. by passing through heat exchanger 16 when entering the heating coil 7.

In the pipes 19 may be arranged suitable purification catalysts by which the impurities in the hydrogen, such as organic sulphur and other compounds, are removed.

Various changes may be made in the details disclosed in the foregoing specification without departing from the invention or sacrificing the advantages thereof.

90 In the claims affixed to this specification no selection of any particular modification of the invention is intended to the exclusion of other modifications thereof and the right to subsequently make claim to any modification not covered by these claims is expressly reserved.

I claim:—

1. In the synthetical production of ammonia by catalytic reaction the step of heating up the hydrogen by bringing same in heat exchanging relation with a foreign hot inert gas, while acting thereon with purifying means.

2. In the synthetical production of ammonia by catalytic reaction the step of heating up the hydrogen by bringing same in heat exchanging relation with a foreign hot inert gas, while acting thereon with a purifying catalyst.

3. In the synthetical production of ammonia by catalytic reaction the step of causing the hydrogen to flow in countercurrent and in heat exchanging relation to foreign hot nitrogen under pressure over a purifying catalyst.

4. The method of carrying out reactions between gases or vapours in reaction chambers comprising conducting fresh gases or vapours first in heat exchange relation to hot gases leaving the reaction chambers and thereafter heating said preheated fresh gases up further by conducting same in heat exchanging relation with a foreign hot inert gas.

5. The method of producing ammonia from hydrogen and nitrogen by catalytic action in a reaction chamber comprising conducting fresh hydrogen in heat exchanging relation and in countercurrent to hot gases escaping from the reaction chamber and then conducting the thus preheated hydrogen in heat exchanging relation and in countercurrent to foreign hot nitrogen under pressure.

6. In the treating and reacting at high temperatures of gases and vapors corrosive to metals at said temperatures, the step which comprises heating such a gas or vapor by bringing it into heat exchanging relation with a hot, confined stream of a foreign, non-corrosive gas under pressures substantially above atmospheric.

7. The process of claim 6 in which the heated foreign gas is passed countercurrent to the gas or vapor to be heated.

8. The process of claim 6 in which the gas to be heated is hydrogen and the reaction is the synthetic production of ammonia.

9. In the synthetic production of ammonia by catalytic reaction, the step which comprises heating the hydrogen required in said reaction by bringing it into heat exchanging relation with a hot, confined stream of a foreign gas under pressures substantially above atmospheric; the said foreign gas being non-corrosive to metals at temperatures approaching reaction temperatures.

10. The process of claim 9 wherein the foreign
gas is nitrogen. 13. The process of claim 9 wherein the foreign
gas is nitrogen heated to a temperature ranging
from about 300° to 400° C. and under high pres-
sures ranging up to 100 atmospheres. 80
11. The process of claim 9 wherein the foreign
gas is heated to temperatures ranging from about
5 300° to 400° C. 14. The process of claim 9 wherein the foreign
gas is heated by passing the same into heat
exchanging relation with a bath of molten metal.
GEORG FRIEDRICH UHDE. 85
12. The process of claim 9 wherein the foreign
gas is maintained at pressures of about 100
atmospheres. 10
